[57] CLAIM

The ornamental design for a body pillow, as shown.

DESCRIPTION

FIG. 1 is a top perspective view of a body pillow showing my new design;

FIG. 2 is a top plan view thereof, the undisclosed bottom being a mirror image of that shown;

FIG. 3 is a front elevational view thereof;

FIG. 4 is a rear elevational view thereof;

FIG. 5 is a left side elevational view thereof; and

FIG. 6 is a right side elevational view thereof.
